(57) **CLAIM**

The ornamental design for a pair of motorcycle tank lifts, as shown and described.

DESCRIPTION

FIG. 1 is a rear exploded view of the pair of motorcycle tank lifts, shown in a position of use.

FIG. 2 is a side view of the pair of motorcycle tank lifts, it being understood that the side view of the second of the pair of motorcycle tank lifts is identical.

FIG. 3 is a side view of one of the pair of motorcycle tank lifts on a reduced scale and shown in a position of use.

FIG. 4 is an enlarged, detailed view of FIG. 3.

FIG. 5 is a side view of one of the pair of motorcycle tank lifts similar to FIG. 3, showing the environmental tank in fully lifted condition; and,

FIG. 6 is an enlarged, detailed view of FIG. 5.

The broken lines shown in the drawing figures are for illustrative purposes only and form no part of the claimed design. Both of the tank lifts of the pair of motorcycle tank lifts are identical to each other. Only one tank lift of the pair of motorcycle tank lifts is shown in FIGS. 2-5 for ease of illustration.
